UNITED STATES PATENT OFFICE.

HARRY ARISTIDE DESPAROIS, OF MONTREAL, QUEBEC, CANADA.

RACK-AND-PINION MECHANICAL MOVEMENT.

1,176,208.

Specification of Letters Patent. Patented Mar. 21, 1916.

Application filed April 5, 1913, Serial No. 759,164. Renewed December 27, 1915. Serial No. 68,943.

To all whom it may concern:

Be it known that I, HARRY ARISTIDE DESPAROIS, a subject of the King of Great Britain, and a resident of the city of Montreal, in the Province of Quebec, in the Dominion of Canada, have invented certain new and useful Improvements in Rack-and-Pinion Mechanical Movements; and I do hereby declare that the following is a full, clear, and exact description of the same.

The invention relates to improvements in measuring pumps, as described in the present specification and illustrated in the accompanying drawings that form part of the same.

The invention consists essentially of the novel construction and arrangement of parts whereby a drawing member is reciprocated during the continuous revolution of an actuating member in one direction.

The objects of the invention are to increase the efficiency of measuring pumps, to facilitate the operation thereof, and, generally, to provide a pump of simple, cheap and durable construction.

In the drawings Figure 1 is a side elevation of the pump. Fig. 2 is a plan view of the top. Fig. 3 is a vertical sectional view of the operating part of the pump broken away and showing the means for operating. Fig. 4 is a vertical sectional view of the operating part of the pump on the line A—B in Fig. 3. Fig. 5 is a side elevation of the operating part showing the sleeve partly broken away. Fig. 6 is a cross-sectional view on the line C—D in Fig. 5. Fig. 7 is a vertical sectional view of the sleeve showing the operating pawl, latch and stops.

Like numerals of reference indicate corresponding parts in each figure.

Referring to the drawings 1 is the pump proper standing on the base 2 and having a piston or drawing member operating therein of a suitable make and not shown or described herein, said piston having a rod 3 projecting upwardly therefrom into a cog bar 4 and being suitably secured to said cog bar. Said cog bar 4 extends upwardly centrally above the table 5, the latter being immediately above the delivery faucet 6. It will be thus seen that, in order to operate the piston of the pump and deliver liquid to the faucet 6, the cog bar 4 must be operated vertically and for this purpose the cog bar is shown in the form of

a vertical rack with teeth on one side thereof. It is quite well known in measuring pumps to operate a vertical cog bar connected with the piston rod and measure the liquid according to the length of the stroke of the piston controlled by the movement of said cog bar, but this invention has to do with the means employed for raising and lowering said cog bar and with determining the length of the stroke.

7 is a sleeve surrounding the cog bar 4 having at the lower closed end thereof a piston rod hole 8 and projecting from the side wall thereof adjacent to the bottom end the boss 9, said boss being pierced for the locking bolt 10 spring-held to its inner position by the spiral spring 11.

12 is a wall adjacent to the top of the sleeve 7, having an opening 13 through which the cog bar 4 projects.

14 is a ball race in the outer side of the wall 12 surrounding the opening 13.

15 is an outwardly projecting flange adjacent to the top of the sleeve 7 and immediately beneath the external thread 16 of said sleeve.

17 is an annular row of teeth immediately under the wall 12 and pointing downwardly.

18 is a ring encircling the opening 13 and having a corresponding part 19 to the ball race 14 inclosing with said wall the ball bearings 20.

21 is a suitable spring on top of the ring 18.

22 is a cap having its flanged wall correspondingly threaded to the external thread 16 and mounted on the top of the sleeve 7, having a central cog bar opening therethrough and engaging said spring 21.

23 is a ring encircling the outer wall of the sleeve 7 below the flange 15, said ring having teeth 24 on the underside thereof.

25 is a pivoted stop secured in suitable lugs on the sleeve 7, intermediate of the height thereof and extending through the wall of said sleeve and having the operating arm 26.

27 is a fixed stop higher up in the sleeve 7 and in vertical alinement with the stop 25.

28 is a base flange standing on the table 5 and inclosing the lower end of the sleeve 7.

29 is a lug projecting laterally from the foot of the cog bar and preferably forming part thereof.

30 is a pivot secured in the lug 29 and

carrying thereon the bill-shaped pawl 31, said pawl springing to its upper position and, in the extreme upper position of the cog bar 4, engaging one of the set of teeth 17 5 and turning said sleeve 7 to the extent of one tooth.

32 is a latch similar to the latch in a door and spring held to its outer position and mounted in one side of the foot 29 and, in 10 the extreme lower position of the cog bar engaging the inner end of the locking bolt 10 and, by reason of the greater strength of the spring on the latch 32, than the spring on the bolt 10, forcing said bolt outwardly 15 against the inward pressure of the spring 11 and thus locking the sleeve under the shoulder 33 of the base flange 28, as well as locking the cog bar by bringing the latch 32 under the stop 34, said stop 34 being pivoted at 35 in the sleeve wall and having an operating arm 36 offset at the upper end and extending through the arc-shaped slot 37 at said end so that the stop 34 may be thrown aside and leave a free path for 20 the upward travel of the latch 32, until it reaches the pivoted stop 25 or the fixed stop 27, as the case may be.

38 is a bearing immediately below the ring 23.

30 40 is a spindle operated by the hand wheel 41.

42 is a gear wheel fixedly mounted on the spindle 40 and engaging the teeth 24 in the underside of the ring 23.

35 43 are vertical keys fixedly secured to the sleeve 7 and sliding through suitable slots in the ring 23 insuring the rotation of said sleeve with said ring on the turning of the gear wheel 42, and yet permitting the free 40 vertical movement of said sleeve through said ring.

It will now be seen that, on turning the hand wheel 41 the latch 32 may be cleared of all stops to its upward movement, thus 45 allowing the cog bar the extreme limit of its vertical movement.

44 is the gear chamber casing supported at the upper end of the frame 39 and having a cog bar opening through the top thereof, 50 a division wall 45 intermediate of the height thereof through which said cog bar extends and an annular slot 46 in the wall thereof, into which said ring 23 extends.

47 are fixed vertical plates extending between the wall 45 and the top of the casing 44, one on each side of the cog bar 4.

48 are the main operating gears fixedly mounted on the shaft 49, the latter being journaled in the plates 47 and projecting outwardly through the wall of the casing 44.

50 is a crank handle rigidly mounted on the outer end of the shaft 49.

51 are gear wheels fixedly mounted on the shaft 52, the latter being journaled in 65 the plates 47 above the shaft 49.

53 are pinions rigid with the gears 48 and coacting with the gears 51 on the operation of the crank handle 50.

54 is a driven gear wheel mounted on the shaft 55, the latter being journaled in 70 the fixed plates 47 on the opposite side of the cog bar, said gear 54 coacting with the toothed side of said bar in the raising and lowering of the pump piston.

56 is a shaft journaled in the plates 47 at 75 the rear side of said cog bar and having the pindle 57 projecting laterally therefrom.

58 is a spring encircling the pindle 57.

59 is a rod pivotally secured to the ring 18 and extending upwardly therefrom and 80 terminating in the eye 60, the wall of said eye being slotted to receive the end of the pindle 57, said spring 58 being compressed between the eye 60 and the shaft 56.

61 are tilting plates pivoted on the shaft 85 55 and joined at their tail ends by the shaft 62 passing through the eye 60, consequently, on the raising of the sleeve 7 the plates 61 will be tilted on their pivot 55 in one direction and on lowering said sleeve 7 they will 90 be tilted in the other direction. The spring 58 pressing against the eye 60 holds the plates steady in each position.

62 are gear wheels turning on shaft 63, the latter being secured in the plates 61 adjacent to the upper ends and in the lower position of the sleeve, said gears 62 coacting with the gear wheels 51.

64 are gear wheels turning on the shaft 65, secured in the lower portions of the plates 100 61 and in the upper position of the sleeve 7 coacting with the gear wheels 48 for the purpose of bringing the cog bar to its lower position after being raised through the coaction of the gear wheels 62 and 51. 105

66 are pinions mounted on the same shaft as the driven gear 54 and coacting with the gear 64 fixed with the shaft 65, thereby completing the train of gears from the operating 110 gears 48 to the driven gear 54 in the lower position of the sleeve 7.

68 are pinions mounted on the same shaft as the driven gear 54 and coacting with the pinions 69 fixed with the gear wheels 62 and completing the train of gears to the driven 115 gear 54 in the upper position of the shaft.

69 is a spring under the sleeve 7 and resiliently supporting said sleeve from the table 5 and surrounding the rod 3.

In the operation of this machine the main 120 shaft carrying the main operating gears is turned by hand or power as may be found most convenient, usually it will be done by electric or other power, though where there is only occasional use of the pump it will be operated by hand with the crank handle as shown in the drawings. The rotation of the main shaft turns the two operating gears mounted thereon which carry the main operating pinions. The secondary operating 125 130

gear coacts with the sets of gears at the upper ends of the tilting plates while the main operating gear coacts with sets of gears at the lower ends of the tilting plates, according to the position of the tilting plates. These sets of gears carried by the tilting plates are so arranged in relation to the operating gears as to drive the cog bar downwardly at much quicker speed than ordinarily, a very important feature, as it very much facilitates the operation of the pump. The sleeve or tube 7 surrounding the cog bar is the controlling member of the positions of the tilting plates and the raising of said sleeve tilts the plates, in order to bring the lower gears in mesh with the main operating gears and thus reverse the direction of rotation of the driving gear which coacts with the cog bar. The cog bar is the actuating member as the foot of the cog bar carries a spring latch and also a spring pawl, both of which members respectively affect the raising of the sleeve. The spring pawl engages the annular row of teeth at the upper end of the sleeve at the completion of a full stroke, which say for instance is for the delivery of one gallon of liquid. This pawl, during the operation of lifting the sleeve, turns the said sleeve to the extent of one tooth marking say one gallon of liquid drawn. The connecting rod from the ring immediately under the cap of the sleeve tilts the tilting plates and the spring surrounding the pintle extending from a fixed bearing holds said plate tilted until the downward stroke is completed, then the sleeve moves downwardly and the rod pulls the tilting plates to their other position ready for the upward stroke. The ring from which the said rod extends does not rotate with the sleeve, but on account of the ball bearings between itself and the inner wall near the upper end the friction is reduced to a minimum and consequently the sleeve will turn easily. The machine may be set for a predetermined number of gallons by turning the hand wheel which operates the ring encircling the sleeve or tube, as for instance, if it is required to pump twenty gallons the sleeve is turned to the extent of twenty teeth and works back to zero by the upward and downward movement of the cog bar, as, at the termination of each upward stroke the sleeve is turned one tooth, therefore there will be twenty gallons pumped by the time it reaches zero. So soon as the sleeve reaches zero the latch at the bottom of the cog bar slides under the pivoted stop immediately thereabove and, at the same time, engages the locking bolt in the sleeve and shoots said bolt under the shoulder of the flanged ring on the table, thereby also locking the sleeve to its lower position.

It will be thus seen that the same operation may be carried on from time to time,

according to the different quantities which are required, and, in this connection, it may be said that any mechanic or electrician skilled in the arts may devise attachments suitable for shutting off the power on the latch and locking bolt reaching their locked positions. In order to measure a smaller quantity, say for instance a quart, the pivoted stop immediately above the latch is moved to one side to allow the escape of the latch therebelow. The bar, as soon as the power has been applied, will move upwardly and stop at the first pivoted dog thereabove and the same operation occurs if, for instance, one half a gallon is required, except that the pivoted dog intermediate of the height of the sleeve will be moved by the operator from the path of the latch and the said latch stopped at the fixed stop above. The same operation of lifting the sleeve occurs following the engagement of the latch with one or other of these stops. This invention may be applied to many different kinds of pumps, and it is, of course, obvious that a suitable form of indicator will be applied to the sleeve to point out the number of teeth within the sleeve in order to facilitate the operation of the aforesaid hand wheel in turning said sleeve.

What I claim is:—

1. In a rack and pinion mechanical movement, the combination with the casing carrying a gear box at the upper end thereof, a reciprocating member operating in said casing, a rod extending upwardly from said reciprocating member and a cog bar at the upper end of said rod and having a lug therefrom, of a gear mechanism having a tilting member affecting the driving gears, a rotative member encircling said cog bar and operated thereby, and a non-rotative member operated by said rotative member and operatively connected with said tilting member.

2. In a rack and pinion mechanical movement, the combination with the casing carrying a gear box at the upper end thereof, a reciprocating member operating in said casing, a rod extending upwardly from said reciprocating member and a cog bar at the upper end of said rod and having a lug therefrom, of a gear mechanism having a tilting mechanism affecting the driving gears, a rotative member encircling said cog bar and operated thereby, and normally locked at zero position, means for setting away zero position and a non-rotative member connecting said rotative member with said tilting member for bringing the said rotative member back to zero.

3. In a rack and pinion mechanical movement, the combination with the casing carrying a gear box at the upper end thereof, a reciprocating member operating in said casing, a rod extending upwardly from said

reciprocating member and a cog bar at the upper end of said rod and having a lug therefrom, of a gear mechanism having a tilting mechanism affecting the driving 5 gears, a sleeve encircling said cog bar and lifted thereby, a ring within said sleeve spring cushioned at the upper end thereof, a connecting rod from said ring to said tilting mechanism, means for locking said 10 sleeve to its lower position, and means for turning said sleeve and releasing said lock for a predetermined period of time.

4. In a rack and pinion mechanical movement, the combination with the casing carrying a gear box at the upper end thereof, a reciprocating member operating in said casing, a rod extending upwardly from said reciprocating member and a cog bar at the upper end of said rod and having a lug 15 therefrom, of a gear mechanism having a 20

tilting mechanism affecting the driving gears, a rotative sleeve encircling said cog bar having teeth at the upper end in an annular row and engaged by said cog bar for rotating said sleeve, a non-rotative ring 25 mounted on roller bearings within said sleeve and suitably cushioned, a latch mechanism at the lower ends of said cog bar and sleeve, an external gear mechanism at the upper end of said sleeve for rotating the 30 latter and a connecting rod joining said ring to said tilting mechanism.

Signed at the city of Montreal, in the Province of Quebec, Canada this 24th day of February, 1913.

HARRY ARISTIDE DESPAROIS.
